AUTOMATIC FILLING DEVICE

William M. Shanhouse, Roslyn Heights, and Ernest Daher, Babylon, N. Y., assignors to S. & D. Development Company, Roslyn Heights, N. Y., a partnership

Application March 24, 1953, Serial No. 344,426

17 Claims. (Cl. 226—99)

This invention relates to a device for automatically filling containers, such as paperboard milk containers and the like.

A primary object of the invention is the provision of an automatic filling device constructed and arranged in such a manner that empty containers may be intermittently conveyed to a filling station in alignment with a vertical supply conduit, the container at the filling station being elevated to a filling position in which the bottom of the container actuates a valve body of the supply conduit so that the container may be filled to a predetermined level without splashing or foaming, after which the filled container is lowered and conveyed away from the filling station simultaneously with the arrival of a fresh empty container thereto.

Another object of the invention is the provision of an automatic filling device of the character indicated wherein the successive operations of conveying, elevation, filling, lowering and conveying are accomplished in timed sequence and in a fully automatic manner, continuous operation of the device merely requiring unskilled labor for loading empty containers at one end and removing filled containers at the other end of the device.

A further object of the invention is the provision of an automatic filling device of the character indicated which is particularly suitable for use with containers of the peaked-top closure type, having shiftable gripping or spreading elements which are operative during the elevation of the container to filling position to spread and open the peaked-top closure of the container thereby permitting entry of the supply conduit within the container.

An additional object of the invention is the provision of an automatic filling device of the character indicated which is constructed and arranged in such a manner that it may be readily adapted for filling containers of various shapes and sizes.

A further object of the invention is the provision of an automatic filling device of the character indicated arranged in such a manner as to prevent a flow of milk or other liquid from the supply conduit in the event that the elevating platform arrives in filling position without carrying an empty container thereupon.

Another object of the invention is the provision of an automatic filling device of the character indicated which is designed in such a manner as to prevent tipping and spilling of the contents of a filled container after it has been conveyed beyond the filling station by automatically interrupting the movement of the conveyor in the event that the filled container at the last station of the device has not yet been removed from the table of the device.

The foregoing objects as well as additional objects and advantages of the invention will be readily apparent in the course of the following detailed description taken in connection with the accompanying drawings, wherein:

Fig. 1 is a front plan view, partly in section, of an

2

automatic filling device embodying the features of the invention the container illustrated being of the peaked-top closure variety;

Fig. 2 is an enlarged detail view of a preferred form 5 of supply valve carried at the lower end of the supply conduit;

Fig. 3 is a sectional view of the device taken on line 3—3 of Fig. 1, the lower frame portion of the device being broken away;

Fig. 4 is a sectional view taken on line 4—4 of Fig. 1 and also illustrates a portion of the endless belt conveyor with the apertures or cut-outs therein for receiving and conveying containers along the table of the device;

Fig. 5 is a schematic view of an electrical control circuit for use in connection with the device, the conveyor actuating means and the platform reciprocating means being diagrammatically illustrated;

Fig. 6 is a fragmentary perspective view of one type 20 of container which may be fed to the device, the container having a peaked-top closure;

Fig. 7 is a view similar to Fig. 6 but showing the top closure flaps in partly open position;

Fig. 8 is an enlarged detail view illustrating the initial 25 stage in the operation of the gripping and spreading element to open the peaked-top closure flaps of the container shown in Figs. 6 and 7 as the container is elevated to filling position;

Fig. 9 is a sectional view taken on line 9—9 of Fig. 8;

Fig. 10 is a view similar to Fig. 9 illustrating a successive stage in the operation of the gripping and spreading element;

Fig. 11 is a sectional view taken on line 11—11 of Fig. 10;

Fig. 12 is a sectional view illustrating a further stage 35 in the opening of the peaked-top closure of the container; and

Fig. 13 is a fragmentary detail view of the upper end 40 of one of the arms of the gripping and spreading element.

Referring first to Figs. 1 and 2, the frame F of the device comprises uprights 10 having at their lower end adjustable levelling tips 11 and supported by suitable longitudinal struts 12 and transverse struts 13 (see Fig. 1). Uprights 10 support a table 14 defining a longitudinally extending channel or well 15 along which containers C may be fed intermittently to the filling station of the device by means of a suitable conveyor system. In the preferred embodiment of the invention the conveyor system conveniently takes the form of an endless belt 16 constructed of stainless steel or other suitable material supported between rollers 17 and arranged in such a manner that the upper course of the belt overlies well 15 while the lower course of the belt extends beneath table 14. Rollers 17 are carried on shafts 18 mounted on suitable framework comprising vertical hangers 19, longitudinal tubular supports 20 and transverse struts 21. In order to adjustably tension belt 16, one of the rollers 45 17 may have its respective shaft 18 journaled between a pair of adjustable telescopic extensions 22 of tubular supports 20, as illustrated on the left side in Fig. 1.

In order to slidably convey containers C toward the filling station along the bottom of well 15, conveyor belt 16 is provided throughout its length with a plurality of equally spaced apertures or cut-outs 23. The shape of cut-outs 23 will, of course, depend upon the shape of the containers being filled and in the embodiment illustrated said cut-outs are preferably square to correspond to the square cross-section of container C. Moreover, the cut-outs are arranged in such a manner and are sufficiently large to accommodate containers of conventionally graduated capacity, such as 1 qt., 2 qt., etc., and to convey each 55 of the containers to a position of predetermined align-

ment at the filling station, as will be more fully described hereinbelow. As best seen in Fig. 4, it will also be understood that square cut-outs 23 are arranged in "diamond fashion" so that the diagonals of said square cut-outs substantially coincide with the longitudinal midline of belt 16, with the vertex corners of adjoining cut-outs adjacent each other. Thus it will be readily seen that as the containers are drawn in the direction of the arrow in Fig. 4, each container will be constantly retained in fixed alignment against the left-hand corner of a respective cut-out 23 despite the fact that the container might be substantially smaller than the conveyor cut-out, as shown.

Suitable means are provided for intermittently actuating conveyor belt 16 in order to feed containers along the well 15 of table 14 toward the filling station of the device. The conveyor actuating means may conveniently take the form of an air cylinder 24 having a reciprocable piston rod 25 formed at its outer end with a depending arm 26. A pusher element or claw 27 is pivotally secured to arm 26 and is provided with an anterior notched end 27a and a posterior notched end 27b which alternately engage opposite corners of a respective cut-out 23 in the lower course of belt 16 during advancement and retraction of piston rod 25. The anterior end of claw 27 is counter-weighted so that anterior notched end 27a will swing downwardly to engage the left-hand corner of cut-out 23 during the advancing stroke of piston rod 25 (see Fig. 1) thereby advancing the belt 16 one step. Upon retraction of claw 27 the opposite end thereof is caused to move downwardly by means of a deflecting finger 28 attached to the air cylinder 24 so that the posterior notched end 27b of said claw will engage the opposite or right-hand corner of cut-out 23 in order to retract the conveyor belt 16 slightly. The purpose of slightly retracting the conveyor belt 16 is to insure clearance between the sides of the container C and the respective sides of a cut-out 23 at the filling station of the device as shown in Fig. 1, so that the container may be readily raised to filling position by the elevator mechanism of the device, as will now be described.

As seen in Figs. 1 and 3 the table well 15 is apertured at 29 at the filling station and provided with flanges 30 for supporting a platform 31 having spaced depending legs 32, preferably four in number. Platform 31 is provided with a central aperture 33 for a purpose to be fully described hereinbelow. Suitable elevator mechanism is provided for raising an empty container C, which has been conveyed to the filling station in rest position supported on platform 31, to filling position where the container is filled and then subsequently lowered back to rest position, as will be more fully described. The elevator mechanism may conveniently take the form of an air cylinder 34 suitably supported on the framework of the device and having a reciprocable piston rod 35 which carries a faceplate or pusher plate 36. Pusher plate 36 is provided with four recesses or dimples 37 suitably spaced apart to correspond to the spacing of platform legs 32 in order to contact said legs and elevate platform 31 and container C during the advancing stroke of piston rod 35, as best seen in Fig. 3. For sanitary purposes air cylinder 34 is preferably provided with a protective jacket or shield 38 of stainless steel or the like which is secured to pusher plate 36. In addition, shroud 38 serves for rotational piston alignment and may serve also as an actuating cam for certain of the switches included in the electrical circuit.

A vertical supply conduit 40 is mounted above table 14 and in alignment with the filling station of the device and platform 31. Supply conduit 40 is supported in a bracket 41 carried at the upper ends of inclined side bars 42 and rear bar 43 and communicates with a supply reservoir (not shown). Supply conduit 40 carries at its lower end a delivery valve 44 having an elevatable valve plug 45 engageable by the bottom of the container C in

its elevated position of Fig. 3 to cause a flow of liquid into the container by gravity feed.

As best seen in Fig. 2, valve 44 preferably comprises a valve body 46 defining an annular valve seat 47 cooperating with the valve plug 45 for normally closing off the flow of liquid in the position shown. Valve plug 45 is formed with an external projection 45a adapted to be engaged by the bottom wall of the container C in its elevated position of Fig. 3 in order to raise said valve plug and permit a flow of liquid into the container. Valve plug 45 is further preferably provided in its upper portion with a plurality of fins or vanes 48 in order to promote uniform flow of liquid. The described arrangement of the valve serves to assure filling of the container without undesirable foaming, splashing, etc.

A fixed outer cylindrical hood 50 surrounds supply conduit 40 and serves as a support for a dismountable inner cylindrical hood or shroud 51 having at its upper end a pair of short locating arms 52 and a relatively long locating arm 53 (see Fig. 4). Shroud 51 is elongated and preferably formed at its lower end with a flared or conical mouth 51a. Outer hood 50 and inner shroud 51 are formed at their respective lower ends with an upwardly turned lip 50a and 51b, respectively, for retaining and disposing condensed moisture and the like. Intermediate its ends at approximately the level of the bottom of outer hood 50, inner shroud 51 is provided with mounting legs 54 and 55 which serve to firmly secure said inner shroud in place as by means of clamping elements 54a and 55a carried by said outer hood. Clamping elements 54a and 55a are preferably of different size to prevent misalignment of inner shroud 51. The described arrangement permits the use of interchangeable inner shrouds of varying dimensions and shape corresponding to the capacity and shape of the containers being filled in a given case. Inner shroud 51 serves to support and guide the container C in proper alignment as the container is elevated from the filling station in the position of Fig. 1 to the position of Fig. 3.

Suitable means are provided for filling the container to a predetermined level and for then actuating the elevator mechanism of the device in order to retract platform 31 and the filled container back to table 14. Such means preferably include a level-detecting contact finger or probe 60 adjustably mounted on an insulating block 61. Probe 60 is electrically connected to a control circuit which governs the conveyor belt and elevator mechanisms of the device in a manner to be fully described hereinafter with reference to the electrical control circuit schematically illustrated in Fig. 5. As will be seen the control circuit is devised in such a manner that when probe 60 contacts the liquid in the container at a predetermined level (see Fig. 3) the probe will be grounded, thereby de-energizing a solenoid which actuates an air valve associated with air cylinder 34 in such a manner as to retract piston rod 35 and lowering the platform 31 and the filled container carried thereupon. The moment the bottom of the container is carried out of contact with external projection 45a of valve plug 45, the valve plug drops against its valve seat 47 (see Fig. 2) and automatically interrupts the flow of liquid. The complete operation of the various solenoid controls and relay switches and the manner in which they govern the movement of the conveyor belt and elevator mechanisms of the device in predetermined timed sequence will be fully described below.

It will, of course, be understood that the device of the present invention may be employed for filling containers of varying sizes and shapes and having a variety of top closure constructions. However, the device may be adapted for use with containers of the familiar peaked-top closure construction such as container C illustrated in the drawings and used frequently for milk and other beverages.

Referring more particularly to Figs. 6 and 7, the

peaked-top closure of container C is of bellows-type construction in which a pair of opposite side walls 64 of the container is provided with a horizontal score line 65, a pair of diagonal score lines 66 converging in an apex 67 and a relatively short vertical score line 68 extending upwardly from apex 67. By reason of the described arrangement of score lines the side walls 64 are adapted to fold inwardly between the side walls 63 to form the peaked-top closure construction shown in Fig. 6. Side walls 63 are formed with inner tuck flap 63a and outer tuck flap 63b and firm closure of the container is obtained, after the container has been filled with milk or any other beverage, by a conventional metal clamp (not shown) which may be crimped over outer tuck flap 63b in the well-known manner. Containers of the type described are constructed of relatively heavy cardboard, paperboard or the like and are supplied with the top closure folded substantially in the position shown in Fig. 6 with inner tuck flap 63a retained between the inwardly folded portions of side wall 64 and an adjacent side wall 63. In order to fill the container it is first necessary to open the top closure to permit insertion of a liquid supply conduit.

In the preferred embodiment of the invention illustrated in the drawings, a gripping and spreading element is associated with inner shroud 51 which serves to open the peaked-top closure of container C as the container is raised to filling position. The construction and operation of the gripping and spreading element 70 will now be described with particular reference to Figs. 8 to 13 inclusive. Element 70 is arranged for free slidable movement within inner shroud 51 and includes a shaft or crossbar 71 having a pair of terminal enlargements such as the spheres 72 which are slidably and rotatably retained within a pair of opposed longitudinal channels 73 formed in the body of said inner shroud. A pair of spaced apart, inclined fingers 74 is rigidly fixed to crossbar 71 and a tripping arm 75 having a roller 76 at its free end is also secured rigidly to said crossbar. As seen in Figs. 1 and 11 the gripping and spreading element 70 is normally in rest position at the lower end of inner shroud 51 with roller 76 of tripping arm 75 resting against flared mouth 51a. At the upper end of each finger 74 a contact member or block 77 is mounted for limited pivotal movement as by means of a pin 78. Shaft or crossbar 71 is preferably, but not necessarily, semi-circular in cross-section. Each block is provided with an arcuate abutment face 79 and a pin 80 (see Fig. 13) between which are engaged opposite ends of the inwardly collapsed side walls 64 of the top closure as the container is raised by the elevator mechanism of the device. Figs. 8 and 9 illustrate the initial stage in the elevation of the container and the opening of the peaked-top closure, wherein opposite ends of the peaked-top closure initially contact the arcuate abutment faces 79 of blocks 77.

The next stage is illustrated in Figs. 10 and 11 wherein, the carton having been but slightly elevated above the level of Figs. 8 and 9, the opposite ends of the peaked-top closure of the container are completely received between the arcuate abutment face 79 and the pin 80 of each block 77. It will be understood that as the carton is elevated from the level of Fig. 9 to the level of Fig. 10 blocks 77 will pivot slightly from their normal position in Fig. 9 to the position of Fig. 10. As the container continues to rise within inner shroud 51, the entire gripping assembly 70 is carried upwardly together with the container with the result that roller 76 of tripping arm 75 initially rides up the flared mouth 51a and then the inner wall of shroud 51, as shown in Fig. 12. Consequently the shaft or crossbar 71 is caused to rotate counter-clockwise as seen in Fig. 12 with simultaneous rotation of fingers 74 outwardly toward the wall of shroud 51. The outward pivoting movement of fingers 74 results in spreading and opening the peaked-top closure of the container so that the supply conduit 40 may then

enter the container, as shown in Fig. 3. It will be noted that the operation of the gripping and spreading assembly 70 does not require any external actuating means, the opening of the top closure being effected solely by the upward movement of the container and the described arrangement of assembly 70 within shroud 51. It will be further noted with particular reference to Figs. 8 and 9 that as the container is elevated it will be supported on opposite sides between the wall of inner shroud 51 and the crossbar 71 of assembly 70. Consequently it will be apparent that the square cut-outs 23 of conveyor belt 16 are arranged as has been previously described so that each container will come to rest on platform 31 in a position of predetermined alignment with respect to supply conduit 40 and inner shroud 51, or more particularly with respect to the gripping assembly 70 of the latter.

The complete cycle of sequential operations will now be described with reference to Fig. 5 which illustrates schematically an electrical control circuit for the device. Fig. 5 also illustrates diagrammatically the conveyor actuating means and the platform elevating means which have been previously described. For the purpose of conveniently tracing out the circuits to the various solenoids and relay switches which control the movement of the conveyor actuating means and the platform elevating means in predetermined timed sequence, the positive lead is illustrated as being heavier and darker than the negative lead of the control circuit. Beginning at the stage in the operation of the device illustrated in Fig. 1, it will be understood that both the conveyor actuating means and the platform elevating means are retracted and that an empty container has just been conveyed to the filling station to rest position upon platform 31. Pusher claw 27 and pusher plate 36 have been retracted by air cylinders 24 and 34 respectively and platform 31 is in rest position supported by retaining flanges 30 of table well 15.

As pusher claw 27 arrives in its retracted position, a tripping arm 85 suitably mounted on piston rod 25 closes switch A. Current now flows through positive lead, through switch A, through switch B, through relay contact C₁ energizing solenoid D₁ and returns to negative terminal. Energization of solenoid D₁ closes relay contact E.

Current now flows through positive lead, through relay E, through solenoid F and returns to negative terminal. Solenoid F controls the movement of an air valve 86 associated with air cylinder 34 so as to alternately supply compressed air at the top and bottom of the cylinder as illustrated in Fig. 5. Energization of solenoid F turns air valve 86 ninety degrees in a clockwise direction from the position shown thereby introducing compressed air at the bottom of air cylinder 34 to elevate platform 31 and the container C. As the container assumes its uppermost or filling position of Fig. 3, the bottom wall of the container contacts external projection 45a of valve plug 45 and opens the valve permitting a flow of liquid into the container.

When the liquid flowing into the container reaches a predetermined level it contacts the probe 60. It will be understood that when the elevator mechanism raised platform 31 switch H closed and switch B opened, switch H being arranged for actuation by the bottom of cylinder shield 38 and switch B by a tripping arm 38a secured to said shield. Now, therefore, current flows through positive lead, through switch H, through solenoid J, through probe 60 (grounded by contact with liquid level) and back to negative terminal.

Energization of solenoid J closes switch K and current flow is now through positive lead, through switch K, through solenoid D₂ and back to negative terminal. Energization of solenoid D₂ opens relay contact E, thereby de-energizing solenoid F whereupon spring 87 retracts solenoid plunger 88 and restores air valve 86 to its normal position illustrated in Fig. 5, introducing com-

7
pressed air at the top of air cylinder 34 and bleeding air from the bottom thereof. Retraction of piston rod 35 results in lowering of platform 31 and container C. Delivery valve 44 closes and shuts off the flow of liquid.

Upon retraction of piston rod 35, switch H is again opened and switch B is closed. Opening of switch H de-energizes solenoid J and opens switch K, thereby de-energizing solenoid D.

Closing of switch B results in current flow through positive lead, through switch A, through switch B, through relay contact C₂ (contact C₂ having been previously closed by the energization of solenoid L through the closing of switch H when platform 31 was raised), through solenoid M and back to negative terminal. Solenoid M controls the movement of an air valve 90 associated with air cylinder 24 so as to alternately supply compressed air at the forward and rear ends of said cylinder. Energization of solenoid M turns air valve 90 ninety degrees from the position shown in Fig. 5 thereby introducing compressed air at the rear of cylinder 24 to advance pusher claw 27 and to simultaneously advance the conveyor belt 16. The advancement of conveyor belt 16 removes the filled container and deposits a fresh empty container at the filling station of the device. As pusher claw 27 advances switch A opens and as piston rod 25 reaches the end of its advancing stroke, tripping arm 85 closes switch O. The closing of switch O energizes solenoid P and results in the opening of relay contact C₂ and the closing of relay contact C₁, thereby de-energizing solenoid M. Upon de-energization of solenoid M, spring 91 retracts solenoid plunger 92 and restores air valve 90 to its position of Fig. 5, thereby introducing compressed air at the front end of air cylinder 24 and bleeding air from the rear end thereof. Pusher claw 27 and piston rod 25 are thus retracted to complete the cycle of operations of the filling device.

The control circuit is also devised in such a manner that platform 31 and the elevator mechanism will immediately retract if the platform is inadvertently raised to filling position without an empty container on the platform. Normally the upper limit of motion of platform 31 is determined by contact of the bottom wall of a container against the bottom of delivery valve 44, as shown in Fig. 3. It will be remembered that platform 31 is formed with a central aperture 33. If no carton is carried upon platform 31, said platform 31 and the elevator mechanism is arranged to rise a slight distance above its normal level by entry of the valve 44 within platform aperture 33, at which point switch 95 is adapted to be closed as by the upper end of protective shield 38 of air cylinder 34. The closing of switch 95 energizes solenoid D₂, opening relay contact E and de-energizing solenoid F to immediately retract the elevator mechanism and platform 31. It is emphasized that switch 95 will not close at the end of the upward stroke of the elevator stroke unless there is no container on platform 31.

Safety switch 96 is provided to prevent tipping and spilling of the contents of a filled carton at the last station on the right-hand side of the device by preventing advancement of the conveyor actuating means unless the carton has been removed. Safety switch 96 is of the normally closed type but will be opened unless the filled container (in broken outline in Fig. 5) is removed from the last station on the right-hand side of the device. If the container is not removed, switch 96 remains open thereby preventing energization of solenoid M and preventing advancement of pusher claw 27 and feeding of the conveyor.

From the foregoing it is apparent that the practice of the present invention provides a filling device having a great number of distinct and considerable advantages over devices of conventional design and construction intended for the same general purpose. The filling device of the present invention is characterized by unusual ease and economy of fabrication since it comprises a minimum

8
number of movable operating components and a minimum number of components requiring precision fabrication; ease and simplicity of design, assembly, operation, adjustment, maintenance and repair; accessibility of components for cleaning, maintenance and repair; high degree of sanitation; safety features for both operator and machine; adaptability for necessary cleaning by steam immersion, or the like; adaptability for uniform and foamless filling operations; elimination of necessity for external reservoir tank used in conventional pump feeding arrangements; elimination of necessity for premeasuring before filling operation is commenced; direct measurement of volume of fill in the container without requiring consideration of factors such as time and/or weight as a result of the cooperative interrelationship of the mechanical components and the electrical system, including the level-detecting probe 60; accuracy and uniformity of filling operation and the provision of pressure necessary for auxiliary operations such as spray cleaning by steam, disinfectants and the like. It is further noted that the electrical system is designed and arranged in such a manner that power failure will result in the immediate and automatic return of platform 31 to rest position, since the de-energization of solenoid F accompanying such power failure allows spring 87 to retract solenoid plunger 88, thereby restoring air valve 86 to its normal position illustrated in Fig. 5, and introducing compressed air at the top of air cylinder 34 and bleeding air from the bottom thereof. As has been previously described, retraction of piston rod 35 results in the lowering of platform 31 and container C and simultaneous closing of delivery valve 44 to effectively interrupt the flow of liquid.

Since certain modifications may be made in the filling device of the present invention without departing from the scope thereof, it is intended that all matter contained in the foregoing specification and shown in the accompanying drawings be interpreted merely as illustrative and not in a limiting sense.

What is claimed is:

1. An automatic filling device for containers comprising a vertical supply conduit having a delivery valve at the lower end thereof, said valve having a valve plug protruding externally thereof and adapted to permit a flow of liquid upon being raised, a horizontal table having a depressed well portion defining a path of conveyance for containers along said table, intermittently operating conveyor means for feeding empty containers to a filling station on said table well in alignment with said supply conduit, an elevatable platform disposed at said filling station, said conveyor means including an endless belt passing above and beneath said table and overlying said table well, said belt having a plurality of receiving apertures permitting insertion of containers for slidable movement along said table well upon actuation of said conveyor belt, reciprocable means disposed between the underside of the table and the endless belt and engaging a portion of the bounding wall of each aperture in successive washion to intermittently move the belt over the table and reciprocable elevator means for raising a container retained on said platform into filling position wherein said valve is opened by contact of the bottom wall of said container against said valve plug.

2. An automatic filling device for containers comprising a vertical supply conduit having a delivery valve at the lower end thereof, said valve having a valve plug protruding externally thereof and adapted to permit a flow of liquid upon being raised, a horizontal table, intermittently operating conveyor means for feeding empty containers to a filling station on said table in alignment with said supply conduit, an elevatable platform disposed at said filling station, reciprocable elevator means for raising a container on said platform into filling position wherein said valve is opened by contact of the bottom wall of said container against said valve plug, and electrical control means including a level-detecting element

carried by the supply conduit operative to cause lowering of said elevator means at a predetermined filling level within the container.

3. An automatic filling device for containers comprising a vertical supply conduit having a delivery valve at the lower end thereof, said valve having a valve plug protruding externally thereof and adapted to permit a flow of liquid upon being raised, a horizontal table having a depressed well portion defining a path of conveyance for containers along said table, intermittently operating conveyor means for feeding empty containers to a filling station on said table well in alignment with said supply conduit, an elevatable platform disposed at said filling station, said conveyor means including an endless belt passing above and beneath said table and overlying said table well, said belt having a plurality of receiving apertures permitting insertion of containers for slideable movement along said table well upon actuation of said conveyor belt, reciprocable elevator means for raising a container retained on said platform into filling position wherein said valve is opened by contact of the bottom wall of said container against said valve plug, and electrical control means including a level-detecting element operative to cause lowering of said elevator means at a predetermined filling level with the container.

4. An automatic filling device in accordance with claim 1 further characterized in that said conveyor means and said elevator means each include a compressed air cylinder having a solenoid-actuated air valve arranged to alternately admit compressed air into opposite ends of said air cylinder for advancement and retraction of the respective actuating means.

5. An automatic filling device in accordance with claim 3 further characterized in that said conveyor means and said elevator means each include a compressed air cylinder having a solenoid-actuated air valve arranged to alternately admit compressed air into opposite ends of said air cylinder for advancement and retraction of the respective actuating means.

6. An automatic filling device for containers having a peaked-top closure, comprising a vertical supply conduit having a delivery valve at the lower end thereof, said valve having a valve plug protruding externally thereof and adapted to permit a flow of liquid upon being raised, a horizontal table, intermittently operating conveyor means for feeding empty containers to a filling station on said table in alignment with said supply conduit, an elevatable platform disposed at said filling station, reciprocable elevator means for raising a container retained on said platform into filling position wherein said valve is opened by contact of the bottom wall of said container against said valve plug, a cylindrical shroud member surrounding said supply conduit and extending below the level of said delivery valve, and a gripping and spreading element slidably retained by said shroud member and operative to open the peaked-top closure of the container upon elevation of the container to filling position.

7. An automatic filling device for containers having a peaked-top closure, comprising a vertical supply conduit having a delivery valve at the lower end thereof, said valve having a valve plug protruding externally thereof and adapted to permit a flow of liquid upon being raised, a horizontal table having a depressed well portion defining a path of conveyance for containers along said table, intermittently operating conveyor means for feeding empty containers to a filling station on said table well in alignment with said supply conduit, an elevatable platform disposed at said filling station, said conveyor means including an endless belt passing above and beneath said table and overlying said table well, said belt having a plurality of receiving apertures permitting insertion of containers for slideable movement along said table well upon actuation of said conveyor belt, reciprocable elevator means for raising a container retained on said platform into filling position wherein said valve is opened by contact of the bottom wall

of said container against said valve plug, a cylindrical shroud member surrounding said supply conduit and extending below the level of said delivery valve, and a gripping and spreading element slidably retained by said shroud member and operative to open the peaked-top closure of the container upon elevation of the container to filling position.

8. An automatic filling device for containers having a peaked-top closure, comprising a vertical supply conduit having a delivery valve at the lower end thereof, said valve having a valve plug protruding externally thereof and adapted to permit a flow of liquid upon being raised, a horizontal table, intermittently operating conveyor means for feeding empty containers to a filling station on said table in alignment with said supply conduit, an elevatable platform disposed at said filling station, reciprocable elevator means for raising a container on said platform into filling position wherein said valve is opened by contact of the bottom wall of said container against said valve plug, electrical control means including a level-detecting element operative to cause lowering of said elevator means at a predetermined filling level within the container, a cylindrical shroud member surrounding said supply conduit and extending below the level of said delivery valve, and a gripping and spreading element slidably retained by said shroud member and operative to open the peaked-top closure of the container upon elevation of the container to filling position.

9. An automatic filling device for containers having a peaked-top closure, comprising a vertical supply conduit having a delivery valve at the lower end thereof, said valve having a valve plug protruding externally thereof and adapted to permit a flow of liquid upon being raised, a horizontal table having a depressed well portion defining a path of conveyance for containers along said table, intermittently operating conveyor means for feeding empty containers to a filling station on said table well in alignment with said supply conduit, an elevatable platform disposed at said filling station, said conveyor means including an endless belt passing above and beneath said table and overlying said table well, said belt having a plurality of receiving apertures permitting insertion of containers for slideable movement along said table well upon actuation of said conveyor belt, reciprocable elevator means for raising a container retained on said platform into filling position wherein said valve is opened by contact of the bottom wall of said container against said valve plug, electrical control means including a level-detecting element operative to cause lowering of said elevator means at a predetermined filling level with the container, a cylindrical shroud member surrounding said supply conduit and extending below the level of said delivery valve, and a gripping and spreading element slidably retained by said shroud member and operative to open the peaked-top closure of the container upon elevation of the container to filling position.

10. An automatic filling device for containers in accordance with claim 6, wherein said shroud member is formed with an outwardly flaring mouth portion and said gripping and spreading element comprises a crossbar, a pair of upwardly extending fingers fixed to said crossbar, contact members mounted at the free ends of said fingers for limited pivotal movement and adapted to engage opposite ends of the peaked-top closure of the container as the container is elevated within said shroud, and a rearwardly extending tripping arm fixed to said crossbar and having a roller at the free end thereof normally engaged against said mouth portion of said shroud member, said arm being operative upon elevation of the container to pivot said fingers and contact members about said crossbar and open the peaked-top closure of the container.

11. An automatic filling device in accordance with claim 7, wherein said shroud member is formed with an outwardly flaring mouth portion and said gripping and spreading element comprises a crossbar, a pair of up-

wardly extending fingers fixed to said crossbar, contact members mounted at the free ends of said fingers for limited pivotal movement and adapted to engage opposite ends of the peaked-top closure of the container as the container is elevated within said shroud, and a rearwardly extending tripping arm fixed to said crossbar and having a roller at the free end thereof normally engaged against said mouth portion of said shroud member, said arm being operative upon elevation of the container to pivot said fingers and contact members about said crossbar and open the peaked-top closure of the container.

12. An automatic filling device in accordance with claim 8 wherein said shroud member is formed with an outwardly flaring mouth portion and said gripping and spreading element comprises a crossbar, a pair of upwardly extending fingers fixed to said crossbar, contact members mounted at the free ends of said fingers for limited pivotal movement and adapted to engage opposite ends of the peaked-top closure of the container as the container is elevated within said shroud, and a rearwardly extending tripping arm fixed to said crossbar and having a roller at the free end thereof normally engaged against said mouth portion of said shroud member, said arm being operative upon elevation of the container to pivot said fingers and contact members about said crossbar and open the peaked-top closure of the container.

13. An automatic filling device in accordance with claim 9, wherein said shroud member is formed with an outwardly flaring mouth portion and said gripping and spreading element comprises a crossbar, a pair of upwardly extending fingers fixed to said crossbar, contact members mounted at the free ends of said fingers for limited pivotal movement and adapted to engage opposite ends of the peaked-top closure of the container as the container is elevated within said shroud, and a rearwardly extending tripping arm fixed to said crossbar and having a roller at the free end thereof normally engaged against said mouth portion of said shroud member, said arm being operative upon elevation of the container to pivot said fingers and contact members about said crossbar and open the peaked-top closure of the container.

14. An automatic filling device for containers comprising a vertical supply conduit having a delivery valve at the lower end thereof, said valve having a valve plug protruding externally thereof and adapted to be unseated by the bottom wall of a container into which the lower end of the supply conduit is positioned, a horizontal

table having a depressed well portion underlying the supply conduit and defining a path of conveyance for containers along the table, an endless belt having an upper reach passing above the table and overlying said table well portion, and a lower reach passing beneath the table, said belt having a plurality of spaced receiving apertures permitting insertion of containers for slideable movement along said table well upon actuation of the conveyor belt, reciprocal means disposed between the underside of the table and the lower reach of the belt and engaging a portion of the bounding wall of each aperture in successive fashion to intermittently move the upper reach of the belt over the table well, said table having an elevatable section underlying the supply conduit and onto which the containers are successively moved by the endless belt and means vertically disposed below the lower reach of the belt for raising said elevatable section of the table with a container thereon to lift the container up to a position receiving the lower end of the supply conduit.

15. An automatic filling device as claimed in claim 14, wherein said elevatable section of the table has depending legs extending vertically between the reaches of the belt and said means for raising said section includes an air cylinder having a reciprocal piston rod, a pusher plate carried by the piston rod and having recesses seating the legs, said pusher plate passing upwardly through one of the apertures in the lower reach of the belt.

16. An automatic filling device as claimed in claim 14, wherein said apertures are square and are disposed in longitudinally spaced diamond fashion on the belt.

17. An automatic filling device as claimed in claim 14, wherein said reciprocal means for moving the belt includes an air cylinder having a reciprocal piston rod having a pivoted pusher element formed at its ends with means engaging opposite end portions of the bounding wall of each aperture.
